Primary Examiner—Sandra L. Morris

[57] **CLAIM**

The ornamental design for a playing card, as shown and
described.

DESCRIPTION

FIG. 1 is a front elevational view of the playing card
showing my new design;

FIG. 2 is a rear elevational view thereof, the dotted line
showing of indicia being for illustrative purposes only and
forming no part of the claimed design;

FIG. 3 is a right side view thereof;

FIG. 4 is a left side view thereof;

FIG. 5 is a top plan view thereof illustrating a deck of
multiple playing cards;

FIG. 6 is a bottom side view thereof; and,

FIG. 7 is an isometric view thereof.

The broken line showing of the deck of cards in FIG. 5 is for
illustrative purposes only, and forms no part of the claimed
design.
